UNITED STATES PATENT OFFICE.

OLIVER P. HIX, OF ROCKLAND, MAINE, ASSIGNOR TO HIMSELF AND ADDITIONAL OLIVER AND GALEN F. HIX, BOTH OF SAME PLACE.

CAR-COUPING.

SPECIFICATION forming part of Letters Patent No. 245,497, dated August 9, 1881.

Application filed June 21, 1881. (No model.)

To all whom it may concern:

Be it known that I, OLIVER P. HIX, of Rockland, of the county of Knox, of the State of Maine, have invented a new and useful Improvement in Railway-Car Couplings; and I do hereby declare the same to be described in the following specification and represented in the accompanying drawings, of which—

Figure 1 is a top view, Fig. 2 a bottom view, Fig. 3 a horizontal section, of portions of the platforms or frames of two cars provided with couplings of my improved kind. Fig. 4 is a front-end view of one of said portions with its coupling. Figs. 5 and 6 are hereinafter explained.

The nature of my invention is defined in the claims as presented.

In such drawings, A and A' are the platform portions, each of which is provided with a sliding bunter, B, which, at its rear end, abuts against a slide, C. In rear of the said slide C is another such slide, D, they being adapted to slide in the direction of the length of the bunter and supported in or by suitable guides a, by which their movements are limited. A longitudinal section of one of these guides is shown in Fig. 5, with an ear, b, from each slide projecting into it. Fig. 6 is a side view of one of the slides with its ears b b. Between the two slides and extending from one to the other of them is a spiral spring, E, through which and an ear, e, projecting from the bunter a slide-rod, F, passes, such rod at its rear end being provided with a shoulder or pin, d. At its front end the slide-rod is jointed to a shackle-hook, G, which, formed as represented and provided with a hole, l, going down through it near its outer end, extends through a guide-slot, e, arranged in the front part of the platform portion. Within the said front part of the platform portion is a flaring mouth, H, one vertical side, f, of which is stationary, the opposite side constituting the inner face of a catch-plate, I. This catch-plate at its outer edge is hinged or pivoted to the frame portion A and abuts against a spring, g, which, fixed in the frame, forces the catch-plate or a projection, h, therefrom against a stop or shoulder, i, of the frame, all being arranged as represented.

A lever, K, fulcrumed in the frame portion A, and connected with the catch-plate I by a

link or connecting-rod, k, and arranged as represented, serves to enable an attendant to retract the catch-plate. Next to the catch-plate is a stationary abutment, L, for the head of the opposite bunter, B, to bring up against on the two cars being coupled.

Each of the platform portions A and A' is provided with a sliding bunter, B, slides C and D, guides a a, spring E, slide-rod F, shackle-hook G, flaring mouth H, catch-plate I and its spring g, lever K, and connecting-rod k, they being arranged within such portions in manner as represented, from which it will be seen that each slide-rod F becomes a carrier to its shackle-hook G; also, that in coupling the two cars the shackle-hook G of each will enter into the flaring mouth H of the other, and press aside the catch-plate I thereof and hook upon such plate at its inner vertical edge as the catch-plate may be forced forward by its spring. It will also be seen that the bunter of each car brings up, not against that of the next car, but against the stationary abutment L thereof, the springs E yielding as the bunters come together, and this independently of the shackle-hooks and their carriers. Each shackle-hook, when coupled with a catch-plate and drawn upon, can move independently of the bunter next to such catch-plate, and also can play or swing laterally.

The hole l in each shackle-hook is to enable the hook, as occasion may require, to be connected with an ordinary draw-bar having a flaring mouth and a link-pin to go down through the latter.

When two cars coupled together are each provided with a car-coupling of my improved kind, as described, they cannot easily become accidentally uncoupled, for should either shackle-hook become broken or disengaged from a catch-plate, or the latter become disarranged, the other shackle-hook and catch-plate will continue to keep the two cars coupled.

Uncoupling of the cars may be effected by means of their levers K, which, on being laid hold of and properly actuated, will cause the two catch-plates to be moved out of engagement with the shackle-hooks, so as to admit of one car being moved away from the other.

What I claim as my invention is as follows, viz:

1. The combination of the bunter B, the

slides C and D, and spring E with the shackle-hook G and its carrier F, all being arranged in the frame A and adapted thereto and to each other, substantially in the manner and to 5 operate as described.

2. The combination of the stationary abutment L and the flaring mouth H and its catch-plate I and the operative mechanism of the latter—viz., the spring g, lever K, and connection-rod k—with the bunter B, slides CD, spring E, shackle-hook G, and its carrier F, all being 10

arranged in the platform-frame A and adapted thereto and to each other, substantially as set forth.

3. In the said car-coupling, the shackle-hook 15 provided with the hole l arranged in it, as and for the purpose specified.

OLIVER P. HIX.
